UNITED STATES PATENT OFFICE.

PASCHAL SARREY AND NORMAN H. HUDSON, OF STOUGHTON, MASSACHUSETTS.

ADVERTISING DEVICE.

Application filed October 14, 1922. Serial No. 594,638.

To all whom it may concern:

Be it known that we, PASCHAL SARREY, a citizen of the United States, and NORMAN H. HUNSON, a citizen of the United States, 5 both residents of Stoughton, in the county of Norfolk and State of Massachusetts, have invented a new and useful Advertising Device, of which the following is a specification.

10 This invention relates to an advertising device and more particularly to a bill board adapted to advertise motion pictures.

The principal object of the invention is to provide in connection with the motion 15 picture bill board means for displaying various advertisements.

Another object of the invention is to provide a novel form of bill board especially adapted to make the embodiment of the 20 invention commercially practical.

The means of attaining these and other objects which might hereinafter appear will be apparent from the following description and the accompanying drawings 25 in which:

Fig. 1 is a front elevation of the advertising device embodying the invention;

Fig. 2 is a vertical section on the line 2—2 of Fig. 1;

30 Figs. 3 and 4 are enlarged detail sectional views on the line 3—3 and 4—4 of Fig. 1; and

Fig. 5 is a plan view of Fig. 4.

Referring to the drawings, the numeral 35 10 represents the back board of the device and is preferably of the configuration shown by Fig. 1, although it may be otherwise formed and instead of being flat it may be curved as is readily apparent. The back 40 board 10 is provided at its edges with the top and bottom strips 11 and 12 and the side strips 13 and 14. Spaced from these edge strips are other strips 15, 16, 17 and 18 forming a central panel 19 which is 45 designed to receive the motion picture advertisement. To permit of the ready insertion and removal of this advertisement, there are provided the retaining members or moulding strips 20, 21, 22 and 23, each 50 of these strips having a reduced end portion 24 to co-operate with the adjacent reduced end portion 24^a of the companion strip to form a joint shown in detail by Fig. 4. The back board 10 is provided with nuts 55 25 which receive the retaining thumb screws

26, which pass through the reduced end portions 24 and 24^a of the moulding strips. It will be understood that while this convenient means for retaining the advertising matter in the panel is highly desirable, 60 it may be dispensed with and the advertising matter may be secured in place by any suitable adhesive material.

Co-operating with the edge and central panel strips are cross strips 27 of which 65 there may be a sufficient number to form a suitable number of outside panels which surround the central panel 19, as clearly shown by Fig. 1. These outside panels are adapted to receive advertisements of various 70 kinds and by reason of the presence of the motion picture advertisement on the same board, it will be understood that the attention of a large number of people will be attracted and focused on the device. 75 The strips which thus divide the board into a central and surrounding panel and the cross strips 27 are preferably provided with coverings 29 of any suitable metal, such as 80 sheet brass.

To permit of the ready insertion of the advertising matter, which will preferably be in the form of card board 30, in the panels 28, the strips 11 to 18 have their lower inner longitudinal edges cut out, as 85 shown more clearly by Fig. 3. It will be understood that in order to insert an advertising card in place, a sufficient number of cross pieces will first be removed and after the card is in place in the panel will 90 be replaced to hold the card or other advertising matter in position.

As a convenient means permitting the ready removal and replacing of the cross strips 27, the outside strips 11 to 14 are 95 provided at spaced intervals with grooves 31 which receive one end of the cross pieces 27. The inside strips 15 to 18 are provided at points opposite to the grooves 31 with buttons 32 with which co-operate spring clips 33 secured to the other end of each of the cross pieces. The cross pieces have recesses 34 to enable the spring clip 33 to snap into position over the button 32. It will thus be seen that in order to remove 100 a cross piece, it is necessary only to lift one end of same from its contact with the button 32 and by reason of the provision of the grooves in the outside strips, the cross pieces can be easily replaced and 110

snapped into position and there held by the co-action between the spring clip 33 and the button 32.

From the foregoing description the construction of the device will be obvious and its advantages will be apparent. The provision of the several cross pieces enables the independent insertion or removal of the several advertising cards and the advertisement of the motion picture or other attraction may likewise be independently inserted or removed. In view of what has been disclosed, certain changes in the construction will suggest themselves but it is to be distinctly understood that while the preferred embodiment of the invention has been herein described and illustrated, the invention is not to be restricted thereto except within the scope of the appended claim.

Having thus described the invention, what is claimed and desired to be secured by Letters Patent of the United States is:

A display device comprising an inner frame, an outer frame, one of said frames being provided with recesses, and the other of said frames being provided with projections, and cross pieces having ends received into said recesses and opposite ends provided with spring clips co-operating with said projections to removably hold the cross pieces in position, said cross pieces having their ends provided with recesses into which said springs may be depressed.

In testimony whereof, we hereunto affix our signatures this 13th day of October, 1922.

PASCHAL SARREY.
NORMAN H. HUDSON.
